UNITED STATES PATENT OFFICE.

ISIDOR ROSENBLATT, OF BROOKLYN, NEW YORK.

DESIGN FOR A CANDLE PLATE FOR LIGHTING FIXTURES.

Application filed February 4, 1928. Serial No. 25,169. Term of patent 3½ years.

To all whom it may concern:

Be it known that I, ISIDOR ROSENBLATT, a citizen of the United States, residing at Brooklyn, in the county of Kings and State of New York, have invented a new, original, and ornamental Design for a Candle Plate for Lighting Fixtures, of which the following is a specification, reference being had to the accompanying drawing, forming part thereof, in which—

Fig. 1 is a side elevation; and
Fig. 2 is a bottom plan view, showing my new design.

I claim:
The ornamental design for a candle plate for lighting fixtures, as shown.

ISIDOR ROSENBLATT.
